UNITED STATES PATENT OFFICE.

LOUIS E. F. WACHTER, OF HARTFORD, CONNECTICUT.

DESIGN FOR A BEAD FOR NECK-CHAINS OR SIMILAR ARTICLES.

No. 39,248.

Specification for Design.

Patented April 7, 1908.

Application filed January 24, 1908. Serial No. 412,522. Term of patent 7 years.

To all whom it may concern:

Be it known that I, LOUIS E. F. WACHTER, a citizen of the United States, residing in the city of Hartford, in the county of Hartford, in the State of Connecticut, have invented a certain new, original, and ornamental Design for Beads for Neck-Chains or Similar Articles, of which the following is a specification, reference being had to the accompanying drawing, forming a part hereof.

The drawing is a view in side elevation of a bead for neck chains or similar articles which embodies the invention.

I claim

The ornamental design for a bead for a neck-chain, or similar article, as shown.

LOUIS E. F. WACHTER.

In the presence of—

W. B. GREELEY,
AMBROSE L. O'SHEA.
